GALVANIZING APPARATUS

Ralph E. Aungst, Avondale, Ohio, assignor to
 Reeves Steel and Manufacturing Company,
 Dover, Ohio, a corporation of Ohio

Application March 9, 1940, Serial No. 323,170

14 Claims. (Cl. 91—12.5)

The invention relates to machines for coating pails, buckets and other pre-fabricated articles with zinc, tin or other coating material.

It is known that machines have been constructed and are being satisfactorily operated for galvanizing pails, buckets and other pre-fabricated articles.

The present invention, therefore, contemplates certain improvements in the construction and operation of machines for galvanizing or otherwise coating pails and similar articles, and has for its objects the provision of a machine which will be simple and inexpensive in construction, and which will occupy a minimum amount of floor space and which will quickly, efficiently and uniformly coat the pails or other articles with spelter or other coating metal.

An object of the invention is to provide a galvanizing machine in which a rotating annulus is associated with the tank or pot containing the molten coating metal, said annulus carrying a plurality of radially disposed arms which support the pails or other articles to be coated, means being provided for axially rotating the arms at predetermined points so as to move each pail through a number of predetermined positions in order to properly coat the pail with metal and drain the surplus coating metal therefrom.

Another object is to provide such a machine in which the rotating annulus dips slightly below the surface of the coating metal at a point intermediate the ends of the tank or pot, a flux box being provided at one end portion of the tank so that the flux floats upon the molten metal, friction means being provided for engaging the sides of the rotating annulus so as to prevent the flux from passing to the other end portion of the tank.

A further object is to provide a novel means for supporting the pails or other articles to be coated.

A still further object of the improvement is to provide an improved scraper or skimmer for removing scale, oxide and other matter from the surface of the molten coating metal just prior to the time each pail emerges therefrom.

The above objects together with others which will be apparent from the drawings and following description or which may be later referred to may be attained by constructing the improved galvanizing machine in the manner illustrated in the accompanying drawings in which—

Figure 1 is a side elevation of the improved galvanizing machine, parts being broken in section for the purpose of illustration;

Fig. 2, a top plan view of the machine with the rotating annulus removed, parts of the mechanism being shown in section;

Fig. 3, a detail sectional view through the improved scraper or skimmer mechanism taken as on the line 3—3, Fig. 2;

Fig. 4, a detail section of a part of the scraper or skimmer mechanism taken as on the line 4—4, Fig. 2;

10 Fig. 5, a fragmentary elevation of a portion of the rotating annulus with one of the radial arms supporting a pail in the position it assumes as it leaves the flux box and enters the coating metal, the radial arm at this point being operated by one of the cam means and the axis of said radial arm being approximately on the line 5—5 shown in Figure 1;

Fig. 6, a detail sectional view taken substantially on the line 6—6, Fig. 5;

20 Fig. 7, a detail sectional view taken as on the line 7—7, Fig. 5;

Fig. 8, a section taken as on the line 8—8, Fig. 1;

Fig. 9, a section taken as on the line 9—9, Fig. 1;

25 Fig. 10, a side elevation of a modified form of the improved galvanizing machine with parts broken in section for the purpose of illustration;

Fig. 11, a plan view of the form of the machine shown in Fig. 10 with the rotating annulus removed and parts broken in section;

Fig. 12, a detail sectional view of the scraper or skimmer mechanism taken as on the line 12—12, Fig. 11;

35 Fig. 13, a fragmentary sectional view of the scraper mechanism taken as on the line 13—13, Fig. 11;

Fig. 14, a fragmentary elevation partly in section showing the reverse side of the rotating annulus from that shown in Fig. 10;

40 Fig. 15, a fragmentary detail plan of a portion of the rotating annulus with one radial arm showing a pail carried thereby; and

Fig. 16, a section taken as on the line 16—16, Fig. 15.

Similar numerals refer to similar parts throughout the several views.

The tank or pot in which the molten spelter or other coating metal is contained may be of any usual construction and is indicated generally at 20, the level of the molten metal being indicated therein by the broken line M.

50 A flux box 21 is shown in the upper portion of the metal pot at the point where the articles to be coated enter the same, the flux floating upon

the top of the molten coating metal at this point, the level of the flux being indicated by the broken line F in Figure 1.

A rotatable wheel or annulus indicated generally at 22 is located above and extends into the metal pot to a point slightly below the surface of the molten metal and through the slot 23 at the inner end of the flux box.

The annulus or rim 22 of the wheel may be connected by spokes 24 with a central hub 25 which is rotatably mounted upon the shaft 26 which may be stationary and supported at its ends by the upright brackets or pedestals 27 mounted upon opposite side walls of the tank or pot 20.

For the purpose of supporting pails, buckets or other ware to be coated, a plurality of preferably radially disposed arms indicated generally at 27 are carried by the wheel or annulus 22 each arm terminating at its outer end in the angled end portion 28 which may be located at substantially a right angle to the body portion of the arm 27.

For the purpose of accommodating pails or other articles of varying sizes the angular end 28 of each arm may be adjustable in length by providing a separate outer end portion 28a adapted to be detachably connected to the portion 28 as by a sleeve 29 and pins 30.

The detachable portions 28a may be made in varying lengths to accommodate the articles of different sizes.

Cradles are formed upon the angular portion of each arm by welding or otherwise fixing thereon a spaced pair of arcuate fingers 31 upon the ends of which the side of the pail or other article as indicated at 32 may rest as illustrated throughout the drawings, and as best shown in Figs. 5 and 6.

For preventing any considerable endwise movement of the pail or other article upon the cradle supports, a stop finger 33 may be formed at the end of the angled portion of each arm 27 in position to substantially contact the bottom end of the pail or the like as shown quite clearly in Fig. 6.

Each radial arm 27 is longitudinally slidably mounted within a sleeve 34 rotatably mounted within a radial bore 35 in the annulus 22, the arm 27 being held against rotation relative to the sleeve by means of the pin 36 in the arm slidably within the slot 37 in the sleeve which permits longitudinal movement of the arm relative to the sleeve.

Each of the sleeves 34 preferably extends outward beyond the periphery of the annulus as shown in the drawings and has a collar or shoulder 38 fixed or formed thereon at a point spaced from its outer end for contact with the periphery of the annulus to prevent inward movement of the sleeve.

A finger 39 is fixed or formed upon the outer end of each sleeve 34 extending in the same general direction as the corresponding angled portion 28 of the radial arm 27 and being preferably slightly inclined toward the same and terminating in the outturned rounded end 40 as best shown in Fig. 6, for the purpose of cooperating with the cradle arms 31 to prevent displacement of the pail or other article carried thereby as the annulus is rotated.

A lever arm 41 is fixed to the inner end of each sleeve 34 forming a shoulder 42 at this end of the sleeve butting against the inner side of the annulus 22 and cooperating with the shoul-

der 38 to prevent longitudinal movement of the sleeve 34 relative to the annulus while at the same time permitting rotation of the sleeve within the annulus.

5 A spring 43 is positioned around the inner end of the sleeve between the arm 41 and the annulus, one end of the spring being engaged around the stop pin 44 on the corresponding lever arm 41, as indicated at 45, the other end of the spring being hooked and engaged over the opposite side of the annulus as shown at 46, the spring acting to normally hold the radial arm 27 and pail 32 in the position shown in Fig. 8, the stop pin 44 contacting the side of the annulus 22 as shown in said figure.

10 A cam 47 is fixed upon the stationary shaft 26 as by the key 48 and may contact the inner ends of the radial arms 27, or preferably, the rounded ends 49 of the sleeves 50 which are adjustably mounted upon the inner ends of the arms 27 as by the set screws 51.

15 A coil spring 52 is located around each radial arm 27 between the shouldered lever arm 41 and the collar 53 which may be fastened upon the arm 27 as by a pin 54.

20 The annulus may be rotated in a clockwise direction, as viewed in Fig. 1, by means of a drive chain 55 leading from any suitable source of power and located over the sprocket wheel 56 upon the hub portion of the annulus.

25 In order to confine the flux to the flux box and prevent it from passing over the surface of the molten metal at the opposite end of the tank or pot, a pair of L-shaped plates 57 is provided for frictional contact with opposite sides of the rotating annulus 22 for cooperating with the rotating annulus to effectively close the slot 23 in the inner end wall of the flux box.

30 These L-shaped plates may be mounted upon the extension 58 of one side wall of the flux box and the bracket 59 by means of pins or rods 60 fixed to the L-shaped plates 57 and slidably mounted within the tubular guides 61 carried by the extension 58 and bracket 59, coil springs 62 being located around said tubular guides and interposed between the L-shaped plates 57 and their supporting structures.

35 The angular ends 63 of the L-shaped plates are pressed tightly against the inner end wall 50 of the flux box at each side of the slot 23 by means of bolts 64 carried by the end wall of the flux box and located through slots 65 in the angular ends 63, springs 66 being interposed between the heads of the bolts and the angular ends of the L-shaped plates to hold the same tightly against the inner end wall of the flux box while at the same time permitting the springs 66 to hold the main portions of the L-shaped plates 57 tightly pressed against the opposite sides of the rotating annulus from a point above the flux level to a point below the level of the molten metal.

40 Thus, the flux is prevented from passing through the slot 23 and along the sides of the rotating annulus to the other end of the tank or pot.

45 A slightly inclined stop or cam 67 is supported upon the flux box or other stationary portion of the machine in the path of the roller 68 upon the end of the arm 41 in position to be engaged by said roller as the pail or other article to be coated is leaving the flux box and entering the molten metal.

50 A cam plate 69 is supported upon the flux box extension 58 or other stationary portion of the

machine in the path of the roller 68, in position to be engaged by the roller as the pail is about to emerge from the molten metal.

At the forward end of the cam plate 69 is a slightly inclined edge 70 leading to a recess 71, the working edge of the cam then being substantially flat as at 72 terminating in the inclined edge 73.

For the purpose of removing scale, oxide, and other matter which usually floats upon the surface of the molten zinc or other coating metal in order that none of this matter is deposited upon the surfaces of the pails or other articles as they emerge from the coating metal a mechanism is included in the machine for scraping this scale and other matter from the surface of the molten metal at the point where the pails emerge therefrom.

This scraping and skimming mechanism is arranged to be operated continuously during the rotation of the annulus 22 and for this purpose a chain or other flexible endless member, as indicated at 74, may be located around a sprocket wheel 75 fixed upon the hub of the annulus and around a sprocket wheel 76 upon the drive shaft 77 of the scraper mechanism, said shaft being journaled in a bearing 78 supported upon the extension 58 or other stationary portion of the machine.

A beveled pinion 79 may be fixed upon the shaft 77 and meshes with a bevel pinion 80 upon the vertical shaft 81 journaled in a bearing 82 mounted upon said extension 58.

A hub 83 is fixed upon the lower end of the shaft 81 and provided with a pair of diametrically opposed tubular arms 84 upon each of which is hingedly mounted a scraper blade 85 provided with spring means 86 for normally holding the blade in vertical position.

Two concentric arcuate guide rails 87 are supported within the tank slightly above the level of the molten metal, as by the radial bars 88 and tangential bars 89 connected to the top of the tank and are located in the path of the scraper blades 85, the blades being rotated in the direction of the arrow shown in Fig. 2 and the forward ends of the rails 87 being tapered as at 90 so as to cause each scraper blade to be swung to a inclined position upon its axis as it moves over the guide rails, the oxide, scale, and other foreign matter being wiped from the blades as they pass over the radial bars 88, each blade dipping down below the surface of the metal to scrape the foreign matter therefrom, as it rides off of the curved guide rails.

In the operation of the machine as illustrated in Figs. 1 to 9, inclusive, the annulus 22 is rotated in a clockwise direction as viewed in Fig. 1.

As each radial arm reaches the position shown at A in said figure the sleeve 50 thereon rides onto the high point of the cam 57 compressing the spring 52 and moving the arm 27 radially outward.

This is the unloading and loading station, the coated pail being easily removed while the cradle arms 31 are separated from the finger 39 and an uncoated pail being immediately placed in position between the cradle arms and finger 39.

Further rotation of the annulus permits the sleeve 50 to ride off of the high point of the cam 57, the spring 52 moving the radial arm 27 radially inward to hold the pail against displacement.

The pail is then carried downward and enters the flux box with its uppermost side element 75

approximately horizontal as indicated at B, to allow free entry of the flux to the interior of the pail.

As the pail is about to leave the flux box and enter the molten metal, the roller 68 upon the lever arm 41 engages the cam stop 67 swinging the lever arm 41 to the position shown in Fig. 7 and rotating the sleeve 34 and arm 27 within the annulus 22 swinging the pail to the position shown in Fig. 5, so as to permit the molten metal to flush any remaining flux from the pail.

Further rotation of the annulus causes the roller 68 to pass out of engagement with the stop cam 67 and allows the spring 43 to return the lever arm 41, sleeve 34 and radial arm 27, with the pail carried thereby, to normal position, the return being gradual due to the resistance or retarding action of the molten metal.

As each pail reaches the point indicated at C, where it is about to emerge from the molten metal, the roller 68 upon the lever arm 41 rides up the inclined surface 70 of the cam 69 and into the recess 71 of said cam, causing the lever arm 41 to swing to the position shown in Fig. 9 as the annulus continues to rotate and the roller 68 rides up onto the flat edge 72 of the cam, rotating the sleeve 34 and radial arm 27 in the annulus and swinging the pail to the position shown in Fig. 9, the pail reaching this position just as the last portion thereof leaves the molten metal and remaining in this position until it reaches the position D in Fig. 1, so as to quickly drain the surplus metal therefrom.

As the roller 68 rides down the inclined edge 70 of the cam, the pail is returned to the normal position, a rapid return with an abrupt stop causing the surplus metal to drain from the chime of the pail.

It should be understood that the operation of the scraper mechanism above described is so coordinated with the movement of the rotating annulus that one scraper blade 85 passes across the surface of the molten metal just prior to the time each pail emerges therefrom so that the surface of the metal is clean and no scale, oxide or other foreign matter is deposited upon the pail as it emerges from the metal.

The coated pail remains in the position shown at E until it reaches the unloading and loading station at A at which time the coating is sufficiently dried to permit the pail to be removed and a new pail placed in position upon the arm 27 in the manner above described.

In Figs. 10 to 16, inclusive, is shown a slightly modified form of the machine in which the rotating annulus 22a is mounted upon a plurality of rollers 100 carried by a bracket 101 and received within the internal annular groove 102 in the annulus.

The bracket 101 may be rigidly mounted upon a stationary shaft 26a carried by the uprights 27a mounted upon the side walls of the tank or pot 20a.

The flux box 21a may be of the form best shown in Fig. 11 and provided with an inward extension 103 which is located within the rotating annulus 22a as best shown in Fig. 10.

With this construction it will be seen that no slot is necessary in the side of the flux box to permit the rotating annulus to pass therethrough, and therefore, no gate or other closure means is necessary, the rotating annulus passing down through the flux and into the molten metal on one side of the extension or end wall 103 of the flux box, then passing through the

molten metal beneath said end wall 103 and upward and out of the metal on the other side of said end wall.

A shaft 104 is journaled through a suitable bearing 105 in the bracket 101 and may be driven from any suitable source of power.

A bevel gear 106 is fixed upon said shaft and meshes with a beveled gear 107 fixed on a shaft 108 journaled in a vertical bearing 109 and having a gear 110 at its other end meshing with the ring gear 111 formed or fixed upon the side of the rotating annulus 22a.

With this drive mechanism operating, the rotating annulus 22a may be continuously rotated at any desired speed in the direction of the arrows shown in Figs. 10 and 14.

Radially disposed arms 27a are slidably mounted for radial movement within the rotating annulus 22a, each arm 27a having an angular outer end 28' upon which is mounted a pair of curved cradle arms 31a, a stop finger 33a being fixed to the end of said angular portion of the arm.

Sleeves 34a are rotatably mounted in bores 35a radially located in the annulus 22a, each of these sleeves having an annular flange 38a at its outer end bearing against the periphery of the annulus.

An arm 41a is connected to the inner end of each sleeve, said arm having a disk 41b formed thereon and connected to the inner end of the sleeve 34a as by the screws 112.

A coil spring 43a is located around the reduced central portion of the sleeve 34a within the bore 35a, one of the springs being connected to the annulus 22a as shown at 43b and the other end of the spring being connected to the sleeve 34a as shown at 43c whereby the arm 41a is normally held in the position shown at G in broken lines in Fig. 15, the stop pin 44a upon the arm 41a contacting the adjacent side of the annulus 22a.

An inclined finger 39a is welded or otherwise fixed upon the outer end of each sleeve 34a and cooperates with the cradle arms 31a for retaining a pail 32a or other article thereby coated in proper position upon each arm 27a.

Each of the arms 27a is slidably located within the corresponding sleeve 34a, a spring 52a surrounding the arm 27a and being interposed between the shoulder 113 in the sleeve, and the collar 53a upon the arm 27a, normally holding said collar against the disk portion 41b of the arm 41a. Diametrically opposed slots 114 may be formed in the sleeve 34a to slidably receive opposite ends of the pin 115 carried by the arm 27a, whereby the arm may be slidably moved longitudinally relative to the sleeve, but is held against rotation relative to the sleeve.

A cam plate 67a may be fixed upon the bracket 101 in position to engage the rounded inner ends 49a of the radial arms 27a for the purpose of slidably moving the radial arms 27a radially outward as they reach the loading and unloading station A' as indicated in Fig. 10.

A cam stop 67a is mounted upon any suitable stationary portion of the machine, such as the side wall 58a of the flux box, in the path of the arms 41a at the point where the pails leave the flux and enter the molten metal, for the purpose of swinging the arms 41a, and with them the sleeves 34a and radial arms 27a to the full line position shown in Figs. 15 and 16 so that the pails assume this position as they enter the molten metal in order to flush any remaining flux therefrom.

A cam plate 69a is mounted upon a stationary

portion of the machine in the path of the arms 41a as the pails emerge from the molten metal in order to swing each arm 41a to the broken line position indicated at H in Fig. 15, swinging the corresponding arm 27a and the pail 32a carried thereby to the position shown at H in Fig. 10 draining the surplus coating metal from the pail, after which the pail is quickly snapped back to the normal position to drain the chime.

5 10 15 20 A scraper mechanism for scraping or skimming oxides, scale, and other foreign matter from the surface of the molten metal just before each pail emerges therefrom is preferably provided in this form of the machine also, and the scraper mechanism shown is the same as that shown and described in detail in connection with the first form of the invention and for this reason no further description of the scraper mechanism is thought necessary and the same reference numerals are applied thereto as used in the above description in Figs. 1 to 9, inclusive.

This scraper mechanism may be operated in unison with the rotating annulus 22a by operatively connecting the chain 74, thereof, to the 25 drive shaft 104.

30 35 40 45 From the description it is believed that the operation of the form of the invention illustrated in Figs. 10 to 16, inclusive, will be obvious and it should be understood in the operation of this form of the machine the pails or other articles to be coated pass through the machine in the same manner as above described.

I claim:

1. Apparatus for coating metal articles, including a tank of molten metal, a flux box at one end of the tank for supporting flux upon the surface of the metal, a rotating annulus supported upon a horizontal axis above the tank with its lower portion dipping below the level of the molten metal, means for rotating the annulus, radial arms carried by the annulus, means upon the radial arms for supporting articles and conducting them through the flux and molten metal when the annulus is rotated, and means for turning the radial arms upon their axes as the annulus rotates.

2. Apparatus for coating metal articles, including a tank of molten metal, a flux box at one end of the tank for supporting flux upon the surface of the metal, a rotating annulus supported upon a horizontal axis above the tank with its lower portion dipping below the level of the molten metal, means for rotating the annulus, radial arms carried by the annulus for supporting articles and conducting them through the flux and molten metal, and cam means in the path of the radial arms and cooperating therewith for turning the radial arms upon their axes as they enter the molten metal.

3. Apparatus for coating metal articles, including a tank of molten metal, a flux box at one end of the tank for supporting flux upon the surface of the metal, a rotating annulus supported upon a horizontal axis above the tank with its lower portion dipping below the level of the molten metal, means for rotating the annulus, radial arms carried by the annulus for supporting articles and conducting them through the flux and molten metal, and cam means in the path of the radial arms as they emerge from the molten metal for turning the radial arms upon their axes as they leave the molten metal.

4. Apparatus for coating metal articles, including a tank of molten metal, a flux box at one end of the tank for supporting flux upon the surface

of the metal, a rotating annulus supported upon a horizontal axis above the tank with its lower portion dipping below the level of the molten metal, means for rotating the annulus radial arms carried by the annulus for supporting articles and conducting them through the flux and molten metal, and two spaced cam means located on opposite sides of the annulus for turning the radial arms upon their axes as they enter and leave the molten metal.

5. Apparatus for coating metal articles, including a tank of molten metal, a flux box at one end of the tank for supporting flux upon the surface of the metal, a rotating annulus supported upon a horizontal axis above the tank with its lower portion dipping below the level of the molten metal, means for rotating the annulus, means upon the annulus for supporting articles and conducting them through the flux and molten metal, there being a slot in the inner end of the flux box 20 through which the annulus rotates, and plates frictionally engaging opposite sides of the annulus adjacent to said slot for preventing the flux from passing through the slot.

6. Apparatus for coating metal articles, including a tank of molten metal, a flux box at one end of the tank for supporting flux upon the surface of the metal, a rotating annulus supported upon a horizontal axis above the tank with its lower portion dipping below the level of the molten metal, means for rotating the annulus, means upon the annulus for supporting articles and conducting them through the flux and molten metal, there being a slot in the inner end of the flux box 30 through which the annulus rotates, and L-shape plates frictionally engaging opposite sides of the annulus and the inner end of the flux box adjacent to said slot for preventing the flux from passing through the slot.

7. Apparatus for coating metal articles including a tank of molten metal, a flux box at one end of the tank for supporting flux upon the surface of the metal, a rotating annulus supported upon a horizontal axis above the tank with its lower portion dipping into the molten metal below the inner end of the flux box, means for rotating the annulus, means upon the annulus for supporting articles and conducting them through the flux and molten metal, and means associated with the tank for turning said article supporting means to tilt the articles as the annulus rotates.

8. Apparatus for coating metal articles, including a tank of coating material, a rotating annulus supported upon a horizontal axis above the tank with its lower portion dipping below the level of the coating material, means for rotating the annulus, radial arms slidably mounted upon the annulus and having article engaging means thereon, cooperating article engaging means carried by the annulus, and means for slidably moving each radial arm at one point to permit unloading and loading of articles.

9. Apparatus for coating metal articles, including a tank of coating material, a rotating annulus supported upon a horizontal axis above the tank, means for rotating the annulus, radially disposed sleeves carried by the annulus and rotatable relative to the annulus, radial arms located through the sleeves and slidably relative to the sleeves, cooperating, article engaging means upon the sleeves and radial arms for supporting articles and conducting them through the coating material, means for slidably moving each radial arm in its sleeve at one point to permit unloading and loading of articles, and means for rotat-

ing the sleeves upon their axes to tilt the articles as they pass through the coating material.

10. Apparatus for coating metal articles, including a tank of molten metal, a rotating annulus supported upon a horizontal axis above the tank, means for rotating the annulus, means upon the annulus for supporting articles and conducting them through the molten metal, a rotating scraper blade supported upon a vertical axis above the tank at the point where the articles emerge from the molten metal for scraping oxide and the like from the surface of the molten metal at the point where the articles emerge therefrom, means for rotating the scraper blade, and means for coordinating the rotation of the annulus and of the scraper blade.

11. Apparatus for coating metal articles, including a tank of molten metal, a rotating annulus supported upon a horizontal axis above the tank, means for rotating the annulus, means upon the annulus for supporting articles and conducting them through the molten metal, a rotating scraper blade supported upon a vertical axis above the tank at the point where the articles emerge from the molten metal for scraping oxide and the like from the surface of the molten metal at the point where the articles emerge therefrom, means for rotating the scraper blade, means for coordinating the rotation of the annulus and of the scraper blade, and means for raising the scraper blade from the molten metal and wiping the surface of the blade during one portion of each rotation of the blade.

12. Apparatus for coating metal articles, including a tank of coating material, a rotating annulus supported upon a horizontal axis above the tank, means for rotating the annulus, radially disposed sleeves carried by the annulus and rotatable relative to the annulus, radial arms located through the sleeves and slidably relative to the sleeves, cooperating, article engaging means upon the sleeves and radial arms for supporting articles and conducting them through the coating material, cam means for slidably moving each radial arm in its sleeve at one point to permit unloading and loading of articles, and cam means for rotating the sleeves upon their axes to tilt the articles as they pass through the coating material.

13. Apparatus for coating metal articles, including a tank of molten metal, a rotating annulus supported upon a horizontal axis above the tank, means for rotating the annulus, means upon the annulus for supporting articles and conducting them through the molten metal, a rotating scraper blade supported upon a vertical axis above the tank at the point where the articles emerge from the molten metal for scraping oxide and the like from the surface of the molten metal at the point where the articles emerge therefrom, means for rotating the scraper blade, means for coordinating the rotation of the annulus and of the scraper blade, arcuate guide rails for raising the scraper blade from the molten metal during one portion of each rotation of the blade, and a substantially radial bar associated with the guide rails for wiping the surface of the scraper blade.

14. Apparatus for coating metal articles, including a tank of coating material, a rotating annulus supported upon a horizontal axis above the tank, means for rotating the annulus, radially disposed sleeves carried by the annulus, radial arms rotatable relative to the annulus, radial arms lo-

cated through the sleeves and slidably relative to the sleeves, cooperating, article engaging means upon the sleeves and radial arms for supporting articles and conducting them through the coating material, a cam engaging the inner ends of the radial arms for slidably moving each arm

5 in its sleeve at one point to permit unloading and loading of articles, a lever arm upon each sleeve, and cam means in the path of said lever arms for rotating the sleeves upon their axes to tilt the articles as they pass through the coating material.

RALPH E. AUNGST.
